UNITED STATES PATENT OFFICE.

HARRY D. NASH, OF TOPEKA, KANSAS.

PIPE-CUTTER.

1,117,225.

Specification of Letters Patent. Patented Nov. 17, 1914.

Application filed April 9, 1914. Serial No. 330,655.

To all whom it may concern:

Be it known that I, HARRY D. NASH, a citizen of the United States, and a resident of the city of Topeka, county of Shawnee, 5 and State of Kansas, have invented certain new and useful Improvements in Pipe-Cutters, of which the following is a specification.

My invention relates to pipe cutters and 10 more specifically to that class thereof designed for use where a pipe is not readily accessible or where no end is presented over which the cutter may be passed in order to position the same about the pipe.

15 The object of my invention is the production of a pipe cutter as mentioned which will be of durable and economical construction and efficient in use.

Other objects will appear hereinafter. 20 With these objects in view my invention consists in the combinations and arrangements of parts hereinafter described and claimed.

The invention will be best understood by 25 reference to the accompanying drawings forming a part of this specification, and in which—

Figure 1 is a side elevation of a pipe cutter embodying my invention, Fig. 2 is a 30 top plan view thereof, Fig. 3 is a section taken on line $x-x$ of Fig. 2, Figs. 4 and 5 are enlarged detail sections taken on substantially lines $y-y$ and $z-z$ respectively of Fig. 1, and Fig. 6 is a perspective view 35 of one of the carriers of the cutter detached.

The preferred form of construction as 40 illustrated in the drawing comprises an annular body adapted, when the device is in use, to be arranged about the pipe which it is desired to operate upon. Said body consists of a main or relatively stationary section 1 and a secondary or relatively movable section 1', said sections being arranged in alinement or end to end in order to constitute 45 a continuous annulus. One end of the section 1' is pivotally connected at 3 to the corresponding end of section 1 in order to permit of the opposite end of said section 1' being swung outwardly as clearly shown in 50 dotted lines in Fig. 1 so as to permit of the device being attached to or removed from a pipe without the necessity of sliding the same to position over an end of the pipe. The contiguous ends of the sections 1 and 1'

are interlocked, that is the respective ends 55 of the section 1 are provided with tongues 4 and 5 which snugly engage with slots 6 and 7 respectively, provided in the contiguous ends of section 1', such arrangement locking the sections 1 and 1' together 60 against any relative lateral movement.

The free end of the section 1' is provided with a latch 8 which is slidably mounted in a socket 9 provided in said section, being locked therein by a nut 10. The inner beveled end of the latch 8 is adapted, when the section 1' is in operative relation with the section 1, to engage a recess 11 provided in the adjacent side of said section 1 in order to releasably lock said sections together, a 65 helical compression spring 12 interposed between a collar 13 formed at the inner end of said latch and the nut 10 serving to yieldingly hold said latch in operative position. The outer end of said latch is provided with an exteriorly projecting head 70 as shown whereby the same may be retracted or pulled outwardly in order to disengage the slot 11 and permit of outward swinging of the section 1'. By beveling 75 the inner end of said latch as shown, upon rocking of said section 1' to closed position, the inner end of said latch as shown, upon rocking of said section 1' to closed position, said latch will automatically move outwardly when the same engages with the adjacent portion of the section 1, being 80 moved into engagement with the recess 11 by the spring 12 when the section 1' reaches its operative position. Thus with this arrangement upon rocking of the section 1' to closed position, the same will be automatically locked in this position.

Formed in the body 1-1' are equally spaced radially extending sockets 14 opening at the inner side of said body as clearly shown in Fig. 3. Snugly fitting said sockets 95 for movement therein radially of said body are carriers 15. Adjustment of said carriers in said sockets is effected by means of screws 16 which are rotatably mounted in the body 1-1' but locked against longitudinal movement therein by means of nuts 17 which engage against collars 18 fixed to said screws. The inner ends of said screws engage female threads 16' in the carriers 15, whereby when 100 said screws are rotated, said carriers will be 105 adjusted in the sockets in which the same are mounted. The outer ends of the screws 16 are provided with exteriorly positioned

heads for manual engagement in effecting the adjustment of said carriers as mentioned.

Mounted in each of the carriers 15 is a cutting element 19 which is movably mounted in a socket 20 arranged in the carrier so as to permit of movement of said cutting element radially of the body of the device. The inner ends of said cutting elements project beyond the inner surfaces of said carriers so that the cutting points 21 thereof will be adapted for engagement with the pipe or other object about which the device is arranged. Said cutting elements are 15 yieldingly held at their inner terminals of movement or in operative positions by means of helical compression springs 22 which are interposed between collars 23 formed upon said cutting elements and nuts 24 which are threaded in the outer end of sockets 20. Also mounted in each of the carriers 15 is a roller 25 which is positioned in a socket 26 formed at the inner side of each carrier. Said rollers are so positioned that 20 the inner sides thereof project beyond the inner surfaces of said carriers and said rollers are arranged in transverse alignment with the cutting elements for contact with the pipe or other object about which the device is arranged as will be readily understood. Through adjustment of the screws 16 the carriers 15 may be moved radially of the body of the cutter in order to move the cutting elements 21 and rollers 25 toward 25 or from each other so as to accommodate pipes of various sizes, one of said carriers being shown in dotted lines in Fig. 3 adjusted inwardly or for engagement with a pipe of smaller size. With this arrangement, upon the device being arranged about a pipe, the screws 16 will be adjusted in order to move the rollers and cutting elements into engagement with the pipe as will be readily understood. Encircling the body 1-1' is an annular member 27 in which is mounted a spring pressed pawl 28 adapted for engagement with ratchet teeth 29 which are formed in the periphery of said body. The arrangement is such, as will be observed, 30 that intermittent rotation of the body 1-1' in order to effect cutting of the pipe by the cutting elements of the device is secured by oscillation of the member 27. Such oscillation of said member 27 is secured by means 35 of an outwardly projecting handle 30 which engages with a socket 31 formed at one side of said member 27. The member 27 is releasably locked in position upon the body 1-1' by means of pins 32 which are removably threaded in said body, projecting therefrom for engagement against one side of the member 27, the latter being held between said pins and shoulders 33 as clearly shown in Fig. 2. With this arrangement it will be 40 seen that, upon removal of the pins 32, the

member 27 may be slid laterally to disengagement. One side of the member 27 is cut away as shown in order to allow for outward swinging of the section 1'.

A cutting device of the construction set forth may be readily and easily arranged about a pipe which is not accessible for engagement by a cutter of the usual type and when clamped upon the pipe is adapted to be readily and easily actuated through oscillation of the handle 30 to effect cutting of the pipe. The construction is comparatively simple and economical and hence may be manufactured at a low cost and will be found efficient in use. 70

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims. 80

Having described my invention what I claim as new and desire to secure by Letters Patent is:

1. A pipe cutter comprising an annular body adapted to be clamped about the object to be operated upon; a plurality of spaced radially movable carriers mounted in said body; cutters yieldingly mounted in said carriers; and means for adjusting said cutters radially in said body, substantially as described. 95

2. A pipe cutter comprising an annular body adapted to be clamped about the object to be operated upon; a plurality of spaced radially movable carriers mounted in said body; cutters carried in said carriers; and manually adjustable screws rotatably mounted in said body but held therein against longitudinal movement and in threaded connection with said carriers for 100 adjusting said carriers in said body, substantially as described. 105

3. A pipe cutter comprising an annular body adapted to be clamped about the object to be operated upon; a plurality of inwardly opening radially disposed sockets mounted in said body; a cutting element and a roller mounted in each of said carriers in transverse alignment with each other for contact with the object about which said body is arranged; and means for adjusting said carriers in said sockets, substantially as described. 115

4. A pipe cutter comprising an annular body adapted to be clamped about the object to be operated upon; a plurality of inwardly opening radially disposed sockets spaced in said body opening at the inner side thereof; a cutting element yieldingly mounted in each of said carriers and a 120

130

5 roller rotatably mounted in each of said carriers for contact with the object about which said body is arranged; and means for radially adjusting said carriers in said sockets, substantially as described.

5. A pipe cutter comprising an annular body adapted to be clamped about the object to be operated upon; a plurality of inwardly opening radially disposed sockets 10 spaced in said body opening at the inner side thereof; a cutting element mounted in each of said carriers for movement about said body; helical compression springs for normally yieldingly holding said cutting 15 elements at their inner terminals of movement; and manually operable means for adjusting said carriers in said sockets, substantially as described.

6. A pipe cutter comprising an annular 20 body adapted to be clamped about the object to be operated upon; a plurality of inwardly opening radially disposed sockets spaced in said body opening at the inner side thereof; a cutting element mounted in 25 each of said carriers for movement about said body; helical compression springs for normally yieldingly holding said cutting elements at their inner terminals of movement; a roller mounted in each of said carriers 30 in transverse alinement with the corresponding cutting element; said cutter elements and rollers being adapted for engagement with the object about which said body is arranged; and manually operable means 35 for adjusting said carriers in said sockets, substantially as described.

7. A pipe cutter comprising an annular

body adapted to be clamped about the object to be operated upon; a plurality of spaced radially movable carriers mounted 40 in said body; cutting elements mounted in said carriers; means for rotating said body, said means comprising an annular member rotatably mounted upon said body; a spring pressed pawl mounted in said member; 45 ratchet teeth formed in the periphery of said body for engagement by said pawl; a handle for manually oscillating said member; and removable outwardly projecting pins on the periphery of said body for releasably locking said member in operative 50 position upon said body, substantially as described.

8. A pipe cutter comprising an annular body consisting of a relatively stationary 55 section and a relatively movable section arranged end to end, one end of said relatively movable section being pivotally connected with the contiguous end of said relatively stationary section; a spring pressed 60 latch for releasably locking the other of said relatively movable sections to the corresponding end of said relatively movable section; and a plurality of cutter elements mounted in said body for engagement with 65 the object about which said body is arranged, substantially as described.

In testimony whereof I have signed my name to this specification in the presence of two subscribing witnesses.
